(57) **CLAIM**

The ornamental design for a fluid end for a pumping system, substantially as shown and described.

DESCRIPTION

FIG. 1 is a perspective view of a fluid end;
FIG. 2 is a front view of the fluid end;
FIG. 3 is a back view of the fluid end;
FIG. 4 is a right side view of the fluid end;
FIG. 5 is a left side view of the fluid end;
FIG. 6 is a top view of the fluid end;
FIG. 7 is a bottom view of the fluid end;
FIG. 8 is an enlarged view taken along line 8-8 from FIG. 2;
FIG. 9 is an enlarged view taken along line 9-9 from FIG. 6; and,
FIG. 10 is an enlarged view taken along line 10-10 from FIG. 7.

The broken lines in the drawings depict portions of the fluid end for a pumping system and form no part of the claimed design.

The long dash dot broken lines in FIGS. 2, 6 and 7 are provided to define the field of enlargement on FIGS. 7-10, the short dash dot broken lines on FIGS. 7-10 define the bounds of those enlarged regions and form no part of the claimed design.
